(57) **CLAIM**

The ornamental design for a surface configuration of a handle for cookware, as shown and described.

DESCRIPTION

FIG. 1 is a top right perspective view of a surface configuration of a handle for cookware showing our new design, the top left perspective view being a mirror image;

FIG. 2 is a bottom left perspective view thereof, the bottom left perspective view being a mirror image;

FIG. 3 is a right side view thereof, the left side view being a mirror image;

FIG. 4 is a rear view thereof;

FIG. 5 is a front view thereof;

FIG. 6 is a top view thereof; and,

FIG. 7 is a bottom view thereof.

The broken lines are for illustrative purposes only and form no part of the claimed design.

1 Claim, 3 Drawing Sheets
